SELECTIVE TRAVEL DRAFT GEAR

Donald F. Sproul, Chicago, Ill., assignor to Cardwell-Westinghouse Company, a corporation of Delaware

Application July 19, 1934, Serial No. 736,002

11 Claims. (Cl. 213—38)

This invention relates to draft gears, and, more particularly, to the friction selective travel type of gear.

One of the objects of the invention is the provision of a new and improved gear having novel means for permitting the gear to have a greater travel in one direction than in the other.

Another object of the invention is the provision of a new and improved selective travel friction draft gear which may be installed in the conventional draft gear pocket on railway cars.

A further object of the invention is the provision of a new and improved selective travel draft gear together with novel means whereby the coupler and yoke may be positioned forwardly of the conventional position for these members without affecting the position of the cooperating friction members or changing the position of the draft lugs.

A still further object of the invention is the provision of a new and improved draft gear that is simple in construction, efficient in operation, composed of a minimum number of moving parts, that may be used in the conventional draft gear pocket of railway cars, and which may be easily and readily installed or removed.

Other and further objects and advantages of the invention will appear from the following description, taken in connection with the accompanying drawings, in which:

Fig. 1 is a horizontal section of a portion of the underframe of a car, showing the invention in position, with parts in section and parts broken away;

Fig. 2 is a longitudinal vertical section on the line 2—2 of Fig. 1;

Fig. 3 is a horizontal section similar to that shown in Fig. 1 showing the gear fully compressed during buff;

Fig. 4 is a view similar to Fig. 3 but showing the gear fully compressed under draft;

Fig. 5 is a perspective view of one of the triangular wedge blocks;

Fig. 6 is a perspective view of the inner casing; and

Fig. 7 is a perspective view of one portion of the outer casing.

It is desirable that draft gears have a maximum travel under buff. But unless proper provision is made for reducing this amount of travel under draft, the coupler head will extend beyond the end of the car an objectionable distance.

Since the shocks due to draft are not so severe as those under buff, it is practical to provide a

shorter travel for the gear under draft than under buff.

The present invention seeks to accomplish this end without requiring any modification of the conventional gear pocket or any change in the position of the wedging elements over what is known by the trade as the conventional Cardwell type of friction draft gear.

While the Cardwell gear is selected to illustrate one embodiment of the invention, it is understood that the principle employed is applicable to other types of gears and that the disclosure is by way of example only.

Referring now to the drawings, the reference characters 10 and 11 designate the conventional center sills of a railway car which are provided with the conventional buffer lugs 13 and 14, and the draft lugs 15 and 16, as is usual in such constructions. The space between the sills 10 and 11 and between the buffering and draft lugs constitutes the conventional draft gear pocket in which the draft gear 17 is located.

The draft gear 17 comprises what for convenience of description will be termed the outer or the forward and rear followers comprising the casings 18 and 19, respectively.

The forward casing 18 is hollow and is open at its rear or inner end. Its forward end is provided with an opening 21 through which a projection on the inner casing extends, as will presently appear. The rear casing 19 is hollow and opens forwardly for receiving the wedging mechanism, as will presently appear.

The casing 19 is provided with a partition 22 which constitutes the bottom or abutment wall of the casing. The casing extends rearwardly beyond the bottom wall, as clearly shown in Fig. 2 of the drawings. This extension has a rear wall 23, which is provided with a depression 24 for receiving the rear end of the yoke 25. The space between the walls 22 and 23 may be solid material, but, preferably, it is cored in such a manner as to provide a plurality of open spaces forming a space framework, thereby lightening the weight of the casing, and, at the same time, properly bracing the same.

An auxiliary follower comprising an inner casing 26 is slidably mounted within the forward portion of the forward casing. This casing is rectangular in cross section, and may also be hollow with proper bracing members 27 cast integral with its walls. The casing 26 is provided with a forwardly extending reduced projection or extension 28 which is adapted to extend through the opening 21 when the gear is expanded. The inner

casing 26 is provided with a rear wall 31 for engaging the wedging mechanism for limiting the compression of the gear, as will presently appear.

Suitable wedging mechanism is provided between the walls 22 and 31. Any suitable mechanism may be employed for this purpose. In the form of construction shown, which is by way of example only, this mechanism comprises a central wedge block 32, end wedge blocks 33 and 34, all of which are provided with wedging or inclined friction faces and with an axial opening through which a tension rod 35 extends. The tension rod extends through slots 30 and 40 in the center sills, as shown in Fig. 4. A plurality of wedge blocks 36 triangular in cross-section are adapted to engage the wedge or inclined faces of the wedge members 32, 33 and 34 at the front and rear thereof, as shown in Figs. 1, 3 and 4 of the drawings. Suitable means are provided for yieldingly forcing the wedge members 33 and 34 inwardly along the bolt to resist the movement of the wedge blocks 36 during the compression of the gear.

As shown, a pair of inner spring seats 37 and 38 slidably mounted on the rod 35 are employed for this purpose. These seats are provided with sleeves 39 and 41 (see Fig. 1) which are adapted to engage the outer surface of the blocks 33 and 34. The sleeves extend through the slots 30 and 40 in the center sills. The inner edges of the casings 18 and 19 are provided with recesses 42 and 43 for receiving the sleeves when the gear is compressed. The outer ends of the rod 35 are provided with outer spring seats 44 and 45 and a plurality of helical springs are mounted on the rod between the inner and outer spring seats at each end of said rod, as shown in Fig. 1 of the drawings.

The wedge blocks 36 are each provided with an inclined face 46 (see Figs. 4 and 5) facing outwardly and with an inclined face 47 facing inwardly. The faces 47 are at a more acute angle to the axis of the gear than the faces 46 so that a prompt release of the gear after compression is insured. The inclination of the faces 46 determines to a large degree the capacity of the gear—the broader the angle, the greater the capacity of the gear.

If desired, suitable means may be provided for insuring the proper positioning of the wedge blocks 36 when the gear is being assembled. The inner ends of the upper and lower walls of the casings 18 and 19 are provided with L-shaped slots 48 and 49 (see Fig. 7) which are turned in reverse direction. The laterally extending portions of these slots are made wide enough to accommodate the movement of the casings. Each of the wedge blocks 36 is provided at one end with a projection or lug 51 which is adapted to engage in either the slot 48 or the slot 49. The slots and projections are so arranged that when the wedge blocks are turned to cause projection 51 to enter the slot and the projection moved along the slot, the block will be in proper position. For instance, it will be seen that if the block 36, shown in Fig. 5, be inserted in the casing 18 in Fig. 7 with the projection 51 engaging the groove 48, the surface 36 will face outward and the block will be on the right side in Fig. 7, but if it be reversed, the projection will enter the slot 49 and the block will be on the left side of the gear with its wedge face 46 facing outwardly. This arrangement not only facilitates assembly, but insures proper positioning of the wedge blocks 36, since they cannot be assembled any other way.

The gear is adapted to be encircled by the yoke 25 which is connected at its forward end to the coupler butt 52 by means of the key 53 which extends through openings in the coupler butt 52 and through the ends 54 of the coupler yoke, as is common in such constructions. The yoke 25 seats in the recess 24, thereby advancing the coupler butt to the position to give the required clearance between the coupler horn 56 and the strike plate 55.

In the operation of the device, when it is operating under buff, the coupler butt 52 will engage the extension 28 of the inner casing, moving the same rearwardly, as shown in Fig. 3, until the rear wall of the inner casing seats on the forward portions of the wedge members 32, 33 and 34, and forces the same into contact with the wall 22, thereby closing the gear.

Under draft, the rear casing 19 is pulled forwardly until its forward edge engages the rear edge of the outer casing 18 for closing the gear. The parts are so constructed that the movement of the inner casing 26 for closing the gear is greater than the movement of the casing 23 for closing the gear under draft.

In practice, the casing 26 is permitted to move $3\frac{1}{2}$ " before the gear closes, and the casing 23 is permitted to move $2\frac{1}{2}$ " before closing the gear. The depression 24 positions the coupler butt forwardly the required distance. In other words, the gear has a travel of $3\frac{1}{2}$ " on buff and only $2\frac{1}{2}$ " on pull or draft.

I claim as my invention:—

1. In a railway car having a strike plate and a draft gear pocket beneath one end thereof and provided with a yoke and coupler butt provided with a coupler horn, attached to said yoke, the combination of a pair of hollow follower casings opposite each other, one of said casings having an opening in its outer end, a wedge friction system between said casings, an inner casing having a reduced portion extending through said opening, said inner casing being between said coupler butt and said systems, and in engagement with said system whereby upon buff said butt will extend through said opening for forcing said inner casing against said system and on draft said first-named casings will limit the travel of said gear, and spring means to restore the parts to normal position after compression.

2. In a draft gear, a follower casing having the interior of its top and bottom walls provided with angular slots arranged in reverse order, duplicate wedge members each having its wedging faces at different angles, each of said wedge members having a projection on one end for interchangeably engaging said slots whereby said slots determine the position of said wedge members and thereby prevent the improper assembling of said wedge members in said casing.

3. In a draft gear, a follower casing having a top, a bottom and an end wall, said end wall having an opening therethrough for receiving the end of a coupler butt, said top and bottom walls each having a groove extending lengthwise of the casing from one edge thereof and then laterally the lateral extension on the bottom wall being in the opposite direction from that on the top wall.

4. In a draft gear, a pair of open-ended main follower casings opposite each other, one of said casings having slidably mounted therein an auxiliary casing, a plurality of friction elements and wedges between the other of said casings and said auxiliary follower and engaging the same, the auxiliary follower and said other follower

engaging certain of said friction elements for limiting the compression of the gear from one end and said main followers engaging for limiting the compression of said gear from the other end.

5. In combination, a pair of center sills, each provided with draft and buffer lugs, a draft gear between the buffer and draft lugs, said gear comprising a front and rear hollow casing, each having an end, side and bottom walls, the end wall of said front casing having an opening therethrough and the end wall of said rear casing having a depression therein, an auxiliary follower having a reduced portion extending into said opening, a wedging system between said auxiliary and rear casing, said system comprising a rod extending through said sills and between the front and rear casing, a plurality of friction elements on said rod, said elements having inclined wedging faces, a plurality of wedge blocks engaging said faces and said auxiliary and rear follower, springs on the ends of said rods for resisting the compression of said system, a draft yoke embracing said gear and seated in said depression and a coupler butt attached to said yoke and engaging said auxiliary follower.

6. In a draft gear, a pair of follower means, wedge friction mechanism between said follower means, resilient elements for resisting the compression of said mechanism, said means engaging certain portions of said mechanism for forming a solid column on compression of the gear for limiting the travel of the gear in one direction, and means at one end of said gear cooperating with one of said follower means at the opposite end of the gear to form a solid column for limiting the travel of said gear in the other direction, the last-named travel of the gear being a greater distance than that of the first named.

40. 7. In a draft gear, a pair of followers spaced apart, friction mechanism between and engaging one of said followers, said mechanism being adapted to go solid for limiting the compression of said gear in one direction, an auxiliary follower on one side of said gear cooperating with one of said followers and engaging said mechanism for limiting the compression of the gear in the opposite direction, resilient means for resisting the relative movements of the parts of said mechanism and for restoring the parts to normal position after release.

8. A draft gear comprising front and rear follower means, friction mechanism between said means for frictionally resisting the compression of said gears on either pull or buff, said mechanism including laterally movable friction elements, springs for resiliently resisting the compression of the gear, means including certain of

said friction elements for limiting the travel of the gear during buff, certain parts of said follower means engaging each other for limiting the travel of the gear under draft to a distance less than the travel under buff.

5. 9. In a draft gear for railway cars, a pair of outer followers, an inner follower, means including friction mechanism for yieldingly resisting the compression of said gear, said outer followers engaging each other for limiting the travel of said gear under draft and said inner follower cooperating with one of said outer followers and with said mechanism to go solid for limiting the travel of said gear under buff, and coil springs having their axes extending at an angle to the axis of the gear for resiliently resisting the compression of the gear and for returning the parts to normal position after compression.

10. In a draft gear for railway cars, a pair of opposed chambered followers, the forward end of the forward follower having an opening therethrough and the rear follower having a portion of its rear end offset forwardly, a draft yoke seating in said offset, an auxiliary follower within said forward follower and having a reduced forward end extending forwardly into said opening, relatively movable friction elements between, and engaging, said auxiliary and rear followers, said elements comprising thrust wedging means engaged by said auxiliary follower, and resilient means for restoring the parts to normal position after compression, said chambered followers being adapted to engage each other for limiting the compression of said gear upon pull to less than its complete compression, the dimension of said auxiliary follower longitudinally of said gear being less than that of said front follower whereby the travel of said gear will be greater when compressed on buff than when compressed on pull.

11. In a draft gear, a pair of main followers normally spaced apart, an auxiliary follower, engaging one of said main followers when the gear is expanded, friction mechanism including wedging members between one of said main followers and said auxiliary follower, and in engagement with the latter and separate therefrom, a draft yoke embracing said followers, a coupler butt engaging said auxiliary follower and movable rearwardly through an opening in the forward follower upon compression of said gear, said main followers being adapted to be brought into contact upon compression of the gear upon pull for limiting the compression thereof to less than its compression on buff, and spring means for returning the parts to normal position after release.

DONALD F. SPROUL.
